US00D968450S

(12) **United States Design Patent** (10) Patent No.: **US D968,450 S**
Tinkley et al. (45) Date of Patent: **** Nov. 1, 2022**

(54) **DISPLAY SCREEN OR PORTION THEREOF WITH GRAPHICAL USER INTERFACE**

(71) Applicant: **Slack Technologies, LLC**, San Francisco, CA (US)

(72) Inventors: **Shannon Tinkley**, Vancouver (CA); **Hubert Florin**, North Vancouver (CA); **Cory Bujnowicz**, Vancouver (CA); **Zachary Coffman Sultan**, Berkeley, CA (US)

(73) Assignee: **Slack Technologies, LLC**, San Francisco, CA (US)

(**) Term: **15 Years**

(21) Appl. No.: **29/825,141**

(22) Filed: **Jan. 28, 2022**

Related U.S. Application Data

(63) Continuation of application No. 29/734,110, filed on May 8, 2020, now Pat. No. Des. 945,445.

CLAIM

The ornamental design for a display screen or portion thereof with graphical user interface, as shown and described.

DESCRIPTION

FIG. 1 is a front view of a display screen or portion thereof with graphical user interface showing the claimed design; FIG. 2 is a second embodiment thereof;

FIG. 3 is a third embodiment thereof; and,

FIG. 4 is a fourth embodiment thereof.

The outer broken lines in the figures show a display screen or portion thereof, and form no part of the claimed design. The other broken lines in the figures show portions of the graphical user interface, that form no part of the claimed design.

1 Claim, 4 Drawing Sheets
